HAT HOLDER

Ernest W. Pfeil, Milwaukee, Wis.

Application November 19, 1948, Serial No. 61,031

4 Claims. (Cl. 211—32)

1

This invention appertains to a hat holder formed from a single blank of sheet material and is an improvement over my prior inventions illustrated in my pending applications Serial Nos. 702,935 and 773,897, filed respectively on October 12, 1946, and September 12, 1947.

One of the primary objects of my present invention is to provide novel means for firmly interlocking the supporting yoke with the face panel, when the yoke is swung forwardly to a hat supporting position, so that the yoke will be held at the desired angle against accidental displacement.

Another salient object of my present invention is to provide novel interlocking means struck out from the face panel and the yoke for effectively supporting and holding the yoke at the lower portion thereof, so as to prevent sagging of the yoke under the weight of a hat.

With these and other objects in view, the invention consists in the novel construction, arrangement and formation of parts, as will be hereinafter more specifically described and claimed and illustrated in the accompanying drawing, in which drawing:

Figure 1 is a front elevational view showing the hat holder struck from a single sheet of blank material and prior to the opening up thereof.

Figure 2 is a view similar to Figure 1, and showing the holder in its set up position with a hat therein.

Figure 3 is a horizontal sectional view through the hat holder taken on the line 3—3 of Figure 2, looking in the direction of the arrows.

Figure 4 is a vertical sectional view through the hat holder taken on the line 4—4 of Figure 2 looking in the direction of the arrows.

Figure 5 is an enlarged fragmentary detail vertical sectional view taken on the line 5—5 of Figure 2, looking in the direction of the arrows illustrating the novel connection between the face panel and the yoke.

Figure 6 is a fragmentary front elevational view partly in section, showing the lower end of the hat holder prior to the bending out of one of the supporting tabs for the bottom of the yoke.

Figure 7 is a view similar to Figure 6 and illustrating the inter-engagement of the tab with the bottom of the yoke after the bending out of the tab, Figure 7 being a section taken on the line 7—7 of Figure 4, looking in the direction of the arrows.

Referring to the drawing in detail, wherein similar reference characters designate corresponding parts throughout the several views, the letter H generally indicates my improved hat holder, which is preferably formed from a single blank of sheet material, such as cardboard.

As illustrated, the hat holder H includes a face plate or panel 10 and struck out from this panel is a front supporting frame or yoke 11 for sup-

porting a man's hat, see Figures 2 and 4. The yoke is of a U shape in front elevation and is cut from the panel 10 and is free from the panel at all points with the exception of the lower horizontal edge thereof, so that a connecting hinge 12 will be provided. At the point of connection of the yoke 11 with the panel 10, the panel and yoke are scored along parallel horizontal lines 13, so that the material will be weakened. This, of course, facilitates the folding of the lower end of the yoke on the panel to provide the hinge and to space the lower end of the yoke a sufficient distance from the panel so that a brim of a hat can be accommodated.

When the hat holder H is in use, the panel can be secured in place on a desired support, such as by the use of a thumb tack or the like and the yoke 11 is swung outwardly from the panel at a desired angle thereto to receive the hat. This yoke 11, is firmly held at the desired angle against accidental displacement by the use of my novelty formed supporting arms 14. These arms 14 are cut and struck out from the panel 10 adjacent to its opposite sides and from the opposite sides of the yoke. As is clearly shown in Figures 1 and 2, the arms 14 are connected at their upper ends, to the panel and their points of connection with the panel are preferably weakened by score lines 15, so that the arms can be readily bent out from the panel. The outer ends of the arms 14 are provided with inwardly directed fingers 16 and these fingers are cut out from the sides of the panel 10. The upper edges of the fingers 16 have formed thereon inserting tongues 17, the purpose of which will later appear. It is to be noted that the inner edges of the arms 14 at their points of connection with the fingers 16 are notched out as at 18 and the purpose of this will also be set forth. Adjacent to the upper end of the yoke 11, the yoke is provided with H-shaped cuts or slots 19 and the extreme side edges of the yoke adjacent to its upper end have formed therein recesses or notches 20.

Upon the bending out of the arms 14 and the outward swinging of the yoke 11, the fingers 16 will engage and support the yoke. In order to prevent the disengagement of the arms from the yoke, the tongues 17 are inserted in the H-shaped slots 19. As the tongues are inserted in the slots, the notches 18 and 20 will mate and interlock. This is best shown in Figure 3.

By this arrangement, the yoke is firmly united with the panel, at the upper end of the yoke and the disengagement of the upper end of the yoke 55 with the panel is reduced to a minimum.

In order to form an adequate support for the bottom of the yoke and to hold the hinge portion 12 in a horizontal plane, so that the bottom of the yoke will be spaced from the panel, I provide novel supporting tabs 21. These tabs 21 are struck out

from the panel 10 and the hinge 12 and are arranged in spaced relation relative to one another. These tabs are joined with the panel along their vertical edges and the panel is scored as at 22, to facilitate the outward folding of these tabs. When the tabs are bent out, and the panel is bent down to form the hinge 12, the upper ends of the tabs are inserted into the hinge portion 12 through the openings formed in the hinge portion by the cutting of the tabs therefrom. The outer edges of the tabs are also cut and notched to provide slots 23 and as the tabs are bent outwardly portions of the hinge 12 will ride into the slots 23 and this is facilitated by the notching of the tabs. This provides a firm interlocking connection between the hinge portion 12 of the yoke 11 and the panel.

The inner edges of the yoke 11 can be provided with bent lips 24 for engaging the crown of the hat, as best shown in Figures 2, 3 and 4.

From the foregoing description, it can be seen that I have provided a novel means for effectively supporting the yoke 11 in a desired relation to the panel 10.

Changes in details may be made without departing from the spirit or scope of my invention, but what I claim as new is:

1. A hat holder formed from a single blank of sheet material comprising a front supporting panel, a U-shaped yoke hingedly connected at its lower end to the panel and movable in a collapsed position within the plane of the opposite face of said panel and to an operative position at an angle to said panel, arms hingedly connected to the upper sides of the panel having inwardly directed fingers for engaging the outer face of the yoke to limit the outward swinging movement of the yoke, said yoke having slots therein, and tongues on the inner edges of said fingers insertable in said slots.

2. A hat holder formed from a single blank of sheet material comprising a front supporting panel, a U-shaped yoke hingedly connected at its lower end to the panel and movable in a collapsed position within the plane of the opposite face of said panel and to an operative position at an angle to said panel, arms hingedly connected to the opposite sides of the panel having inwardly directed fingers for engaging the outer face of the yoke to limit the outward swinging

movement of the yoke, said yoke having slots therein, and tongues on the inner edges of said fingers insertable in said slots, the outer edges of the yoke being notched and said arms and fingers being notched at their points of connection, the walls of said notches interlocking when the tongues are inserted in said slots.

3. A hat holder formed from a single blank of sheet material comprising a front supporting panel, a U-shaped yoke hingedly connected at its lower end to the panel and movable in a collapsed position within the plane of the opposite faces of said panel and to an operative position at an angle to said panel, and arms hingedly connected at their upper ends to said panel having inwardly directed fingers for engaging the outer face of the yoke to limit the outward movement of said yoke, the outer edges of the yoke adjacent to their upper ends being provided with notches and said arms and fingers at their points of connection having notches, the walls of the notches interlocking upon the outward swinging movement of the arms and the yoke.

4. A portable hat holder struck from a single blank of sheet material comprising a front panel, a yoke hingedly connected at its lower end to the panel, said hinge including an offset horizontal connecting portion between the yoke and panel, means for limiting the outward swinging movement of the upper end of the yoke, tabs bent out from said panel and offset connecting portion having their upper ends insertable in the offset portion, when said offset portion is in a horizontal plane, and the outer edges of said tabs having notches and communicating slits for receiving edges of the offset portion to hold said offset portion in a set up horizontal position.

ERNEST W. PFEIL.
